UNITED STATES PATENT OFFICE.

GEORGE HUNZINGER, OF NEW YORK, N. Y.

CHAIR.

SPECIFICATION forming part of Letters Patent No. 357,388, dated February 8, 1887.

Application filed September 3, 1886. Serial No. 212,584. (No model.)

To all whom it may concern:

Be it known that I, GEORGE HUNZINGER, of the city and State of New York, have invented an Improvement in Chairs, of which 5 the following is a specification.

This invention relates to the class of chairs in which the back yields to pressure from the person seated in it.

I make the base of the chair with triangular 10 side frames rigidly connected together, and to this base the back-frame is pivoted. The seat-frame is also pivoted to the front part of the base-frame, and the arm-pieces extend from the apex of each side frame to the back-frame, and these arms are extensible and provided with contractile springs. By this construction the back-frame will yield, and the 15 spring-arms will extend so that the chair-back can be inclined, and the seat-frame, being suspended at the back edge from the back-frame, accommodates itself to the position of the other parts.

In the drawings, Figure 1 is a vertical section through the chair seat and back, a portion 20 of the arm also being in section; and Fig. 2 is a front elevation of the chair.

The base-frame is composed of the front legs, A, the inclined back legs, B, connected at their upper ends to the front legs, and the 25 horizontal rails C, uniting the front and back legs, and the cross-rails D, uniting the respective triangular frames of the base.

The back-frame E is usually rectangular, or 30 nearly so, and it is pivoted at F to the back legs, B. The seat-frame G is pivoted G' to the front legs, A, and at the back such seat is suspended from the back-frame E, preferably 35 by the flexible material forming the upholstering. The seat-frame and back are to be caned, upholstered, or otherwise completed, 40 as usual.

The arm-pieces extend from the upper ends 45 of the front legs, A, to the back-frame E, and these arm-pieces are each formed of a rod or bar, H, fastened to the front leg, a rod or bar, K, fastened to the back leg, and a saddle-piece, I, inclosing the contiguous ends of the bars H and K, the saddle-piece I forming an arm-rest and inclosing the contiguous ends of

the bars H and K, and this saddle-piece is 50 preferably connected to the bar K. Beneath the bars H and K, and within the saddle-piece, there is a contractile spring, M, the ends of which are connected, respectively, to said bars H and K, preferably by the downwardly-projecting pins O. When pressure is applied against the back-frame by a person seated in the chair, the back-frame will swing upon its pivots F and the springs M will be extended, and these springs will contract and restore the 55 parts to their normal position when pressure upon the back is relieved.

By this improvement the chair is rendered very comfortable for the person sitting in the same, as the back will remain in a more or 60 less inclined position, according to pressure applied to the same, and a rocking motion may be given to the back, if desired, the arm-rests moving with the back and sliding backward and forward at their front ends upon the 65 bars H.

I am aware that compression-springs have been used between the sliding parts of chair-arms; also, that a chair has been provided with a pivoted back, a seat hinged at its front 70 end, with the rear end of the seat resting loosely on supports on the lower end of the back, and in which the weight on the seat tends to raise up the back.

I claim as my invention—

1. The combination, with the base having 75 triangular side frames, of the back-frame pivoted to the base, the seat-frame pivoted to the front legs and suspended at its back edge from the back-frame, and the extensible spring arm-pieces between the upper ends of the front 80 legs and the back-frame, substantially as set forth.

2. The base-frame formed of the front legs, the inclined back legs connected at their upper ends to the front legs, and the connecting-rails, in combination with the back-frame pivoted to the back legs, the seat-frame, and the extensible yielding arm-pieces between the upper ends of the front legs and the back-frame, 85 substantially as set forth.

3. The combination, with the base-frame, the pivoted back-frame, and the seat pivoted

near its front edge and suspended from the back-frame, of the bars H, connected to the upper ends of the front legs, the bars K, connected to the back-frame, the saddles I, forming arm-rests and covering the adjacent ends of the bars H K, and the contractile springs within the saddle-pieces and connected at their

ends to the respective bars H K, substantially as set forth.

Signed by me this 27th day of August, 1886, to
GEO. HUNZINGER.
